UNITED STATES PATENT OFFICE.

FERNAND JAVAL, OF PARIS, FRANCE.

DESIGN FOR PAPER OR SIMILAR ARTICLE.

61,270.

Specification for Design.

Patented July 25, 1922.

Application filed April 7, 1922. Serial No. 1,617. Term of patent 14 years.

To all whom it may concern:

Be it known that I, FERNAND JAVAL, a citizen of the Republic of France, residing at Paris, (whose post-office address is % Parfumerie Houbigant, 19 Rue du Faubourg Saint-Honore, Paris France), have invented a new, original, and ornamental Design for Paper or Similar Article, of which the following is a specification, reference being had to the accompanying drawing, forming a part thereof.

The drawing shows a perspective view of a portion of paper embodying my design.

I claim:

The ornamental design for paper or similar article, substantially as shown.

FERNAND JAVAL.
